UNITED STATES PATENT OFFICE.

WILLIAM H. ACKERMAN, OF BRIDGEPORT, CONNECTICUT, ASSIGNOR OF
ONE-THIRD TO CHARLES W. H. WALL, OF SAME PLACE.

SHUTTER-OPERATING DEVICE.

SPECIFICATION forming part of Letters Patent No. 541,058, dated June 18, 1895.

Application filed February 9, 1895. Serial No. 537,766. (No model.)

To all whom it may concern:

Be it known that I, WILLIAM H. ACKERMAN, a citizen of the United States, and a resident of Bridgeport, in the county of Fairfield and State of Connecticut, have invented certain new and useful Improvements in Shutter-Operating Devices, of which the following is a specification.

This invention relates to improvements in devices for operating shutters of windows, doors, or the like.

It is the object of my invention to provide means whereby the position of shutters may be controlled from the inside of the window to which they are attached, and also to provide reliable means for retaining the shutters in any desired position, whether open, closed, or at an intermediate station.

It is a further object of my invention to so construct and arrange the mechanism, as to permit of the shutters being removed at will, for the various purposes of washing, painting, repairing, &c.

The same numerals of reference denote like or corresponding parts upon the several figures of the drawings, of which—

Figure 1 shows a perspective view of a window provided with a pair of shutters fitted with my improvements. Fig. 2 is a cross-section on line 2 2 of Fig. 3, looking in the direction of the arrows. Fig. 3 is a sectional plan of Fig. 1, the parts being in a corresponding position. Fig. 4 is a front elevation of a detachable spring-hinge for opening the shutters. Fig. 5 is a perspective view of the chain-securing device. Fig. 6 is a perspective view of the chain-securing device as seen from the rear. Fig. 7 is an inverted plan of the guide L.

Referring to the letters of reference upon the several figures of the drawings, A indicates a suitable window frame, B the sill of the frame, and C C the sash, all of which may be of any ordinary or preferred construction since my improvements are equally applicable to all.

Referring to the perspective view Fig. 1, I have illustrated the shutter D in its extreme open position, and the other shutter D' in a closed position. From this it will be seen that the shutters are adjusted independent of each other and may be independently re-

tained in their open, closed, or intermediate positions.

E represents hinges by means of which the shutters are hung, and as shown are preferably attached upon the upper and lower face. These hinges may be of the usual or any preferred construction, and form no part of the invention.

As before stated the mechanism by means of which the shutters are operated is alike upon each, and therefore I will refer to them with like letters of reference. Upon the lower inner corner of the shutter is a common form of catch F, which ordinarily serves to hold the shutter in its open, or closed position. As shown (see Fig. 2) when the shutter is thrown to its open position the catch F will automatically engage the staple G secured to the outside finish of the house.

In order to normally hold the shutter open, I employ a specially constructed detachable hinge H, which may be placed about midway of the height of the shutter. This hinge consists of leaves a and b, a pivotal pin c, and a torsional spring d. The leaf a, as is apparent, is secured to the shutter by means of small screws, and the leaf b is detachably secured to the frame by means of said leaf being retained between said casing and an angle iron l, secured to the frame. The torsional spring d serves to force the shutter open by having its ends e and f engaging the hinged leaves a and b respectively.

Attached to the catch F which appears upon the lower corner of the shutter, is a small chain J which serves as a line by which the shutter is drawn closed, or partially so against the resistance of the spring actuated hinge H. A forked bracket K serves to support the chain J when the shutter is thrown to an open position as clearly appears in Figs. 1 and 3, and serves to prevent the chain from binding against the shutter. From the bracket K the chain passes through a metal guide L which is secured to the sill of the window frame. Said guide has its inner edges rounded to insure a free movement of the chain. From said guide the chain is passed under a small notch g in the bottom of the lower sash C and then through the bore n in the stool. The stool M of the inside window casing fin-

ishes above the notch *g*, and thus rain is prevented from being driven in through said notch in the bottom of the sash.

In order to retain the chain at any desired point, I have provided the novel device which I have illustrated in detail in Figs. 5 and 6. This device consists of a small casting *N*, which is secured to the face of the window stool *M* by means of screws. It is formed with 10 a beveled hole *h* in the back thereof, orifices *i* and *k* in the front thereof, and a slot *l* through the bottom. A slide *O* having a vertical slot *m* serves to fit into the top orifice *i*, and is attached to the end of the chain *J*. 15 The purpose of this slide is to absolutely close the openings through which the chain enters, and thus prevents the entrance of cold air, or rain. It further serves as a catch for the prevention of the drawing out of the chain, should 20 the notch in the bottom not be desired.

The operation of the device is as follows: If it be desired to open the shutter when closed, the operator would simply remove the slide *O* from the catch, detach the link of the 25 chain from the slot *l* and allow the chain to draw out through the casing, by the action of the spring actuated hinge upon the shutter. After the shutter has been swung out to the desired point the chain would be again secured to the catch.

Having thus described my invention, what I claim, and desire to secure by Letters Patent, is—

1. In a device of the class described the combination with a detachable shutter, of a detachable hinge for normally holding said shutter open, a chain for adjusting said shutter, guides *K* and *L* through which the chain is operated, openings through the sash and window 35 stool to receive the chain, a catch upon the inside of the window frame provided with a hole *h* and orifice *k*, a slot *l* in the bottom of said orifice in which to drop a link of the chain. 40

2. In a device of the class described the com-

bination with a detachable shutter of a 45 detachable hinge for normally holding said shutter open, a chain for adjusting said shutter, guides *K* and *L* through which the chain is operated, openings through the sash and window stool to receive the chain, a catch upon the inside of the window frame and provided with hole *h* and orifice *k*, a slot *l* in the bottom of said orifice, the orifice *i* and a detachable slide *O* to fit therein and straddle a link of the chain. 50

3. In a device of the class described the combination with a shutter and means for normally holding said shutter open, of a line secured to said shutter and passing through the sash, a catch upon the inside of the window frame and provided with a hole *h* and orifices 60 *i* and *k*, a slot *l* in the bottom in which to drop a link of the chain.

4. In a device of the class described the combination with a shutter and means for normally holding said shutter open, of guides *K* and *L* through which the chain is operated, openings through the sash and window stool to receive the chain, a catch upon the inside of the window frame and provided with hole *h* and orifices *i* and *k*, a slot *l* in the bottom 70 in which to drop a link of the chain, a slide *O* adapted to fit into an orifice of the casing and straddle a link of the chain.

5. In a shutter operating device the combination with the shutter, of a line by which to 75 draw the shutter closed, and means upon the inside of the window to secure said line, a spring actuated hinge secured to the shutter and detachably attached to the window frame substantially as described. 8c

Signed at Bridgeport, in the county of Fairfield and State of Connecticut, this 2d day of February, A. D. 1895.

WILLIAM H. ACKERMAN.
